UNITED STATES PATENT OFFICE.

RASMUS P. CHRISTENSEN, OF BUFFALO, NEW YORK, ASSIGNOR OF ONE-HALF TO
CLARENCE O. JOHNSON, OF BUFFALO, NEW YORK.

RECORD-REPEATING DEVICE FOR SOUND-REPRODUCING MACHINES.

1,340,525.

Specification of Letters Patent. Patented May 18, 1920.

Application filed October 5, 1918. Serial No. 257,048.

To all whom it may concern:

Be it known that I, RASMUS P. CHRISTENSEN, a citizen of the United States, residing at Buffalo, in the county of Erie and State 5 of New York, have invented certain new and useful Improvements in Record-Repeating Devices for Sound-Reproducing Machines, of which the following is a specification.

10 My invention relates to improvements in record repeating devices for sound reproducing machines.

This invention is an improvement on an application for patent filed by me on the 15th day of March, 1917, Serial No. 154,944, and embodies the same principles therein shown and described; it, however, has for its object to improve and simplify the construction of the parts to render the device 20 easier to operate and to reduce the cost of the same.

With these objects in view, the invention consists in the novel features of construction and in the arrangement and combination of parts to be hereinafter described and more particularly pointed out in the subjoined claims.

In the drawings,—

Figure 1 is a perspective view of the upper end of a sound reproducing machine of popular style, to which my improved repeating device is attached, part of the cover only being shown.

Fig. 2 is a plan view of the machine with the cover removed.

Fig. 3 is a transverse section through one-half of the upper portion of the sound reproducing machine with the cover removed, the repeating device being shown in normal 40 position.

Fig. 4 is a similar view with the repeating device in a position in which it serves to automatically return the tone or reproducer arm with its sound box or reproducer to the 45 starting point of the record, or to any other desired point from which the record is to be repeated.

Fig. 5 is a horizontal section on an enlarged scale taken on line 5—5, Fig. 3.

50 Fig. 6 is a perspective view of one of the stop devices adjustable on the skid or guide arm of the device, said skid or guide arm being shown in dotted lines to better illus-

trate the application of said stop device to said arm.

55

Fig. 7 is a detached perspective view of the other stop device adjustable on the skid or guide arm of the device, said skid or guide arm being shown in dotted lines to better illustrate the application of said stop device to said arm.

60

Fig. 8 is a transverse section on an enlarged scale taken on line 8—8, Fig. 3.

65

Fig. 9 is a transverse section on an enlarged scale taken on line 9—9, Fig. 3.

Fig. 10 is a transverse section on an enlarged scale taken on line 10—10, Fig. 4.

60

Fig. 11 is a longitudinal section taken on line 11—11, Fig. 9.

65

Fig. 12 is a horizontal section taken on line 12—12, Fig. 3.

Referring now to the drawings in detail, like numerals of reference refer to like parts in the several figures.

The reference numeral 1 designates the sound reproducing machine having a casing 2 including a cover 3, partly shown in Fig. 1, hinged to the body portion of the casing in the usual manner. The body portion of the casing has a top wall 4 and a curb wall 5 projecting upward from the marginal portion of said top wall. Within the space bounded by said curb wall is situated the rotatable disk carrier 6 which is secured to a spindle 7 in the usual manner, said spindle being rotated by motor mechanism (not shown) with which machines of this type are invariably equipped.

8 designates a disk which is placed upon the rotatable carrier 6 and against which is held the stylus or other contact device 9 of a sound box or reproducer 10 supported on a vertically swinging end portion 11 of a tone or reproducer arm 12 arranged for horizontal swinging movement over the record disk, but in machines of different makes the sound box or reproducer is differently supported, all of which, however, forms no part of this invention.

I wish here to state that this invention is 100 designed for use in connection with different makes of sound reproducing machines, and in preferred form comprises a support or standard 13 having a suitable base 14 and a hollow upwardly tapering tubular portion 15 into which is adapted to fit a non-rotat-

- table sleeve 16 which projects upwardly beyond the upper end of said standard and is provided with a longitudinal groove 17 into which the end of a set screw 18 is entered, 5 said set screw being arranged through the wall of the tubular portion of said support or standard so as to hold said sleeve against rotation and also against longitudinal movement within said tubular portion.
- 10 A spindle 19 is fitted into the sleeve 16 so as to rotate therein, said sleeve is split lengthwise, as at 20, and serves to clamp around the spindle entered therein and act to frictionally hold the spindle against accidental rotation. The lower end of the spindle projects beyond the lower end of said sleeve and has a pin 21 passed therethrough which bears against the lower end edge of said sleeve, thereby holding the spindle 15 against lengthwise movement within the sleeve.
- 15 Formed integral with the spindle 19 at the upper end thereof is a channeled head 22 comprising a bottom 23 and spaced sides 24. A stop pin 25 projects from the bottom 23 of said head and is adapted to oscillate within a notch or cut-away portion 26 formed at the upper end of the sleeve 16, the limit of movement of said stop pin being 20 shown in Fig. 5 of the drawings.

25 Pivottally mounted in the channeled head 22 by means of a horizontal, or substantially horizontal, pivot pin 27 is a skid or guide bar 28 which is preferably curved in an arc 30 of a circle having its axis coincident with the axis of the tone or reproducer arm 10. Said skid or guide bar is preferably constructed of bar material of rectangular formation in cross section, and at the end there- 35 of opposite its pivotal connection to said channeled head, it is provided with a longitudinal bore 29 in which a shaft 30 is fitted, said shaft having secured to its outer end a weighted eccentric wheel 31. The 40 skid or guide bar 28 has a longitudinally-disposed slot 32 formed in its under side which opens into the bore 29 in which the shaft 30 is journaled, said slot being somewhat shorter than said shaft, as clearly 45 shown in Fig. 11. The shaft 30 is provided with a longitudinal groove 33 having an abrupt side 34 and an inclined or curved side 35 extending from the innermost point of said abrupt side outwardly to the outer per- 50 55 60 65 70 75 80 85 90 95 100 105 110 115 120 125 130

70 As clearly shown in the drawings, the support or standard 13 is screwed or otherwise secured to the top wall 4 of said casting at a point in close proximity to the peripheral edge of the disk carrier, and the skid or guide arm 28 extends inwardly from 75 this support on a curved line to a point

near the spindle 7, the upper portion of which latter extends through the opening 36 in the record disk 37 placed upon said record carrier.

When the skid or guide bar 28 is properly positioned over the disk, the stop pin 25 on the head 22 is in engagement with one end of the notch or cut away portion 26 of the friction sleeve 16 and holds said bar in operative position, the friction created by reason of the sleeve 16 being split and therefore clamped around the spindle 19 serving to retain said skid or guide bar in operative position, although positively prevented from moving in one direction only by said stop pin engaging the end of the notch or cut-away portion 26. When the tone or reproducer arm is swung to the position shown in dotted lines in Fig. 2, the stop pin 25 is in contact with the opposite end of said notch or cut-away portion 26, as shown by dotted lines in Fig. 5.

Arranged on the sound box or reproducer 10 in any suitable manner is a guide wheel or roller 38, which is designed to travel in contact with the upper face of the skid or guide bars 28, at least in one direction. In the drawings I have shown said guide wheel or roller as adapted to travel in contact with said skid or guide bar during both the inward and outward movements of the sound box or reproducer, but if desired this wheel or roller may be positioned out of contact with said arm during the inward movement without in any manner effecting the operation of my device.

The eccentric wheel 31 is preferably provided with a rubber or other soft contact portion 39, which is adapted to travel in contact with the record disk at certain times during the operation of the device, as will presently be explained. In preferred form this eccentric wheel comprises a segmentally-shaped solid portion 40 which serves as an over-balancing weight and is secured to the shaft 30 journaled for rotation in the skid or guide bars 28, and a circular rim 41 formed of wire and having a rubber tube surrounding the same which forms the contact portion 39 of said wheel and which is in contact with the curved edge 43 of said segmentally-shaped solid portion 40, the end of the wires being brought together, as at 44, and entered into the solid portion 40 of said wheel, as clearly shown in Fig. 9 of the drawings.

The major portion or throw of the eccentric wheel is normally directed upwardly and by reason of the construction described, the weight of the same is greatly reduced, which is highly desirable in a device of this kind.

It will be noted upon examination of Figs. 9 and 10, that the shaft 30 is closer to one of the straight lined edges of the

solid portion 40 than the other, and when the eccentric is released from the position shown in Fig. 9, this solid portion or over-balancing weight tends to rotate the wheel 5 in the direction of the arrow 45 in Fig. 9.

The skid or guide bar is provided with two stop devices 46, 47 which are adjustable lengthwise along said bar, the device being formed of a strip of metal bent into the 10 form of a loop 48 into which the skid or guide arm is fitted, said loop having an upwardly extending arm 49 around which a rubber sleeve or other cushion 50 is placed. The loop 48 also has a laterally and inwardly directed arm 51 thereon, the inner end 52 of which determines the point at which the stylus of the reproducer or sound box is to be positioned when starting to play a record, or when repeating said record.

To one side of the loop 49 a spring retainer 53 is secured, said retainer being riveted to the side of said loop and being adapted to act against the adjacent side of 25 the skid or guide bar to retain said stop device in any position along said bar. Said spring retainer is preferably formed of a strip of spring material bent inwardly to form contact points which bear against the 30 adjacent side of said skid or guide bar, as at 54, thence rebent to provide two converging portions 55, and finally bent at a slight angle to said converging portions to provide 35 spaced finger pieces 56, which when forced together will move the contact point 54 of said retainer away from the skid or guide bar so as to permit the stop device to be easily adjusted along said skid or guide bar. When said stop device is positioned at the 40 desired point along said skid or guide bar, the releasing of the finger pieces 56 permits the contact points 54 to spring against the side of the skid or guide bar and act to retain said stop device in its adjusted position.

The stop device 47 comprises a loop 57 constructed similar to the loop of the stop device 46, with the exception that instead of having the upwardly directed arm 49, it is provided with an arm 58 extending toward the 45 free end of said skid or guide bar, and to this arm is pivotally secured a trip-lever 59 having a trip pin 60 extending laterally over the top of said skid or guide bar. Said trip lever is also provided beneath its pivot point with a laterally-directed arm 61 from the free end of which an upwardly-extending lock-lip 62 projects, said lock lip being adapted to pass through the slot 32 of said skid or guide bar and enter the 50 groove 33 in the eccentric shaft 30. It is to be noted that this lock lip is spaced comparatively close to the axis of the pivot pin 59, whereas the trip pin 60 is a considerable distance from said axis. The increased 55 length of that portion of the trip lever hav-

ing the trip pin 60 thereon and the additional weight of said portion serving at all times to position said trip pin the desired distance from the upper face of said skid or guide bar and to retain said lock lip 70 in elevated position so as to bear against the eccentric shaft either within the groove thereof or against the peripheral face thereof, depending upon the position of said shaft.

The stop device 47 is provided with a spring retainer 63, which is constructed like the retainer 53 of the stop device 46, and acts against the side of the skid or guide arm in the same manner.

The indicating arm 64 of the loop 57 extends toward the pivoted end of said skid or guide arm and the free end thereof is adapted to be positioned over the desired point of the record disk at which the inward movement of the stylus is to be stopped. It will therefore be apparent from the foregoing that the movement of the stylus secured to the sound box or reproducer is in accordance with the distance between the 85 free ends of the indicating arms formed on the stop devices 46, 47 and that these stop devices are adjustable lengthwise of the skid or guide bar so that the entire record piece may be rotated as often as desired, or 90 so that any portion of the piece may be repeated.

With the parts in normal position the major portion or throw of the eccentric wheel 31 will, as above stated, be directed 100 upwardly so that said wheel is out of contact with the record disk, and when in this position, the shaft of said wheel is positioned with the groove 33 thereof in registration with the slot 32 in the skid or guide bar. 105 When the parts are thus positioned, the lock lip 62 of the stop device 47 is passed through said slot 32 and enters the groove 33 of said shaft, with the abrupt side 34 of said groove in contact with said lock lip, said lock lip being retained in locking position by the weight of that portion of the trip lever 59 having the trip pin 60 extending therefrom. At such times the skid or guide bar is substantially in a horizontal position, it being 110 thus supported from the channeled head 22 at the upper end of the spindle 20. The stop device 46 is adjusted to a position along the skid or guide bar in which position the free end of the indicating finger 51 is located directly over the outermost point of the playing portion of the record disk so that when starting the machine it is simply necessary to position the tone or reproducer arm so as to bring the guide wheel or roller 38 against 115 said stop. This will place the stylus of the sound box or reproducer in position to reproduce the piece on said record disk. During the playing of said piece, the sound box or reproducer and the stylus gradually 120

travel inwardly toward the axis of said record disk and at the end of the piece the guide wheel or roller 38 will engage the trip pin 60 of the trip lever 57, causing said lever to 5 swing on its pivot and the lock lip 62 of said lever to move out of the groove 33 of the eccentric shaft, whereupon the over-balancing portion of the eccentric wheel causes said wheel to rotate until the peripheral edge thereof comes in contact with the record disk, and as said record disk continues to 10 rotate said eccentric wheel is continued in its rotary movement, which causes the operating axis of said wheel to be elevated, there- 15 by inclining the skid or guide bar to the position shown in Fig. 4. During the upward movement of said skid or guide bar, the stylus is moved out of contact from the record disk, due to the sound box or reproducer 20 being elevated and when said skid or guide arm is inclined sufficiently, the guide wheel or roller 38 begins to travel along said skid or guide bar in a reverse direction until brought in contact with the stop device 46. 25 When reaching this point, the stylus is still elevated from the record disk and is gradually lowered during the latter half of the rotatable movement of said eccentric wheel, this lowering movement being gradual so 30 that the stylus is gently lowered against said disk. As the eccentric wheel begins to move out of contact with the record disk, the over- balanced portion of said wheel will continue to cause the wheel to rotate until the groove 35 in the shaft thereof is brought in proper position with respect to the slot 32 in the skid or guide arm and during the last portion of this rotary movement the lock lip 62 of the trip lever 57 rides in contact with the curved 40 face 35 of said groove until the abrupt face 34 of said groove comes in physical contact with said lip, whereupon the rotary movement of said shaft and the eccentric wheel thereon is arrested until the guide wheel or 45 roller 38 again operates the stop lever 57.

It will be apparent from the above that if only a portion of the piece on the record disk is to be repeated, either the stop device 46 or the stop device 47 is adjusted and it 50 is to be noted that by reason of the groove 33 being extended almost the entire length of the eccentric shaft 30 and the slot 32 in said arm being substantially coextensive with said groove, a considerable range of adjust- 55 ment is provided for the stop device 47, while the range of adjustment for the stop device 46 is substantially unlimited. If desired, the eccentric shaft 30 may be extended a greater distance into the skid or guide bar 60 28, the groove thereof lengthened, and the slot in the skid or guide bar may be correspondingly lengthened so that the range of adjustment of the stop device 47 may be increased. For all practical purposes, how- 65 ever, it is believed that an adjustment of the

length indicated by the groove 33 in the eccentric shaft and the slot 32 in the skid or guide bar meet all requirements of present day reproducing machines.

As constructed, the gradually increasing 70 distance between the axis of the eccentric wheel and the peripheral edge of said wheel causes a gradual rising of the skid or guide bar during the first half of the revolution of the eccentric, and during the last half the 75 gradually diminishing distance between said axis and peripheral edge causes a gradual lowering of the skid or guide bar, with the result that the stylus of the sound box or reproducer is gently lowered into position 80 against the record disk and with greater care than can be generally exercised when manually placing the stylus in contact with the disk.

It is also to be noted that by reason of said 85 eccentric wheel being positioned close to the axis of the record disk the rotary movement of said wheel is comparatively slow so that sufficient time is provided for returning the tone or reproducer arm with its stylus and 90 for positioning said stylus into contact with the record disk.

Having thus described my invention, what I claim is:—

1. A record repeating device, comprising 95 a support, a guide member pivotally secured at one end to said support and normally retained in horizontal position, means at the other end of said guide member for lifting said member into inclined position including 100 an eccentric having a shaft journaled longitudinally in said guide member, a pair of stops on said guide member, one of said stops including a movable element adapted to engage the shaft of said eccentric and re- 105 tain the same in normal position.

2. The combination with a reproducer arm, of a support having a split sleeve therein; a spindle within said sleeve and frictionally retained against accidental ro- 110 tary movement therein, means for securing said sleeve against rotary movement within said support, a guide member pivotally se- 115 cured to said spindle and adapted to rotate therewith and to have vertical movement in- 120 dependently thereof, lifting means at the free end of said guide member, and a stop- 125 ping device on said guide member serving to limit the movement of said reproducer arm to one direction and acting to retain said lifting means in normal position, said stop- 130 ping device having a combined stop and lock element adapted to release said lifting means when engaged by said reproducer arm to cause return movement of said reproducer arm.

3. The combination with a sound repro- 130 ducing machine having an oscillating re- 135 producer arm and a rotatable carrier on which a disk record is adapted to be placed,

of a support secured to said machine adjacent said carrier, a sleeve secured within said support, a spindle frictionally entered into said sleeve and having an elongated chan- 5 neled head at its upper end, means for limiting the rotatable movement of said spindle and head, a guide member pivotally secured to said head and adapted for vertical swinging movement, a stop on said guide member, 10 a second stop on said guide member including a pivoted lever, a shaft journaled lengthwise in said guide member and having a groove adapted to be engaged by said lever, a weighted eccentric secured to said shaft 15 and normally out of contact with said disk record, and means on said oscillating reproducer arm adapted to engage said lever and disconnect the same from said shaft so as to permit said weighted eccentric to automatically 20 rotate into contact with said disk record, the rotation of said eccentric being continued by said record disk to cause said guide member to assume an inclined position and compel the means on said reproducer arm to travel down the inclined guide member until engaging said first-mentioned stop.

4. The combination with a sound reproducing machine having an oscillating reproducer arm and a rotatable carrier on which a disk record is adapted to be placed, a support secured to the casing of said machine adjacent said carrier and having a vertical bore therein, a split sleeve fitted into 30 said bore and having its upper end projecting beyond the upper end of said support, said sleeve being provided with a notch at its upper end forming a stop, a spindle fitted within said sleeve and frictionally retained therein against accidental rotating movement, said spindle being provided with means to engage said stop and limit the rotating movement of said spindle in one direction, a guide member pivotally secured 35 to said spindle and normally held in horizontal position, lifting means on said guide member for inclining the same toward said spindle, and means on said reproducer arm adapted to cause actuation of said lifting 40 means so as to incline said guide member.

5. The combination with a sound reproducing machine having a movable reproducer arm and a record carrier on which a record is adapted to be placed, a support secured to the casing of said machine adjacent said carrier and having a vertical bore therein, a split sleeve fitted into said bore and having its upper end projecting beyond the upper end of said support with a notch 50 at said end forming a stop, means for securing said sleeve within said bore to prevent rotating and longitudinal movement thereof, a spindle fitted within said sleeve and held against accidental rotation by the friction of said sleeve thereagainst, said spindle

having a channeled head at its upper end and a projection on said head projecting into said notch to limit the rotating movement of said spindle and head in one direction, a guide member pivotally secured to 70 said channeled head and adapted for rotating movement with said head and for vertical swinging movement independent of said head, lifting means on said guide member adapted to be brought into actuation for 75 swinging said guide member upwardly, and means on said reproducer arm adapted to cause actuation of said lifting means when said reproducer arm reaches a predetermined point in its movement.

6. In a record repeating device for sound reproducing machines, the combination of a guide bar, means at one end thereof for changing the position of said guide bar, and a stop device on said guide bar having 80 a locking portion adapted to retain said means in normal position, said stop device having said locking portion actuatable to release the same from said means and permit the latter to change the position of said 85 guide bar.

7. In a record repeating device for sound reproducing machines, the combination of a guide bar having an opening therein, a stop device on said guide bar, and a lifting 90 device carried by said guide bar including a grooved shaft journaled in said guide bar, said stop device including a pivoted lever having a stop member and a lock member adapted to pass through said opening and 95 enter the groove of said shaft.

8. The combination with a sound reproducing machine and a movable reproducer arm, of a guide member arranged along the path of said reproducer arm and pivotally 105 connected at one end, a shaft journaled lengthwise in said guide member and having a longitudinal groove therein, said guide member having a longitudinal slot with which said groove may register, a stop device adjustable along said guide member and having a movable stop member adapted to be engaged by said reproducer arm, said stop member having a locking portion extending through the slot of said guide mem- 110

ber and entering the groove of said shaft, and an eccentric on said shaft, said movable stop member when engaged by said reproducer arm causing said locking portion to become disengaged from the groove of said 115 shaft and permit said eccentric to swing and cause said guide member to assume an inclined position, for the purpose set forth.

9. In a record repeating device for sound reproducing machines, the combination of 120 a guide bar, and a stop device comprising a loop fitting onto said guide bar, a lever pivotally secured to said loop at one side thereof and having a stop member extending laterally therefrom, and a spring retainer 125 130

secured to the other side of said loop and adapted to engage said guide bar.

10. In a record repeating device for sound reproducing machines, the combination of a guide bar having a longitudinal slot in its under side and a longitudinal bore into which said slot opens, a shaft journaled in said bore having a longitudinal groove, an eccentric secured to said shaft, a loop fitting onto said guide bar, a lever pivotally secured to one side of said loop and having a stop member at its upper end extending transversely of said guide bar and an upwardly extending locking portion at its

lower end adapted to pass through said slot 15 and enter the groove of said shaft.

11. In a record repeating device for sound reproducing machines, the combination of a guide bar having a longitudinal slot, lifting mechanism carried by said guide bar 20 and including a shaft journaled therein having a longitudinal groove, and a stop device adjustable lengthwise on said guide bar including a movable stop member having a locking portion adapted to extend through 25 said slot and engage the groove of said shaft.

In testimony whereof I affix my signature.
RASMUS P. CHRISTENSEN.
